J. G. BERGER

WINDING AND SETTING MECHANISM FOR WATCHES

Filed July 21, 1925

BY

J. G. Berger

ATTORNEY.

UNITED STATES PATENT OFFICE.

JOHN G. BERGER, OF BRECKENRIDGE, TEXAS.

WINDING AND SETTING MECHANISM FOR WATCHES.

Application filed July 21, 1925. Serial No. 45,001.

This invention relates to watches and more particularly to that type of watch equipped with stem winding and setting mechanism, in which is employed a sleeve, arranged to co-act with the stem, to hold the latter in respective setting and winding position within the pendant, and the primary object of the invention is to provide a substitute for this sleeve whereby threading of the interior periphery of the pendant may be dispensed with.

The invention further contemplates the provision of a device to facilitate the winding and setting of a watch, and by the elimination of certain present elements of assembly, affords a more durable and practical winding and setting mechanism more accessible to repair.

A further aim of the invention is to provide an exterior means to interiorly control the actuation of the winding stem, such means being durably and substantially constructed and co-acting with the other mechanism in such a manner as to obviate possible fracture or causing injury to such mechanism or the controlling means.

With the foregoing and other objects and advantages in view, the invention has particular reference to certain novel features of construction and arrangement of parts, by which said objects are attained, and which will be set forth and manifested in the course of the following detailed description and illustrated in the accompanying drawings, wherein:

Figure 1 represents a vertical cross-section of a watch pendant, whereon the invention appears.

Figure 2 is a side elevation in vertical section, further illustrating the function and application of the invention.

Figure 3 shows a modified form of the invention.

Figure 4 illustrates an L shaped slot in the watch pendant, whereby the invention is actuated to control the movement of the stem interiorly of the pendant.

Figure 5 is a perspective view of a modified form of the stem controlling device, as applied in Figure 3.

Figure 6 represents an equivalent structure to that shown in Figure 5.

Figure 7 is a plan view of the pendant, showing the position of the controlling device depicted in Figure 5, and

Figure 8 is a similar view, showing the position of the equivalent structure, illustrated in Figure 6.

Figure 9 is a view of a watch case partly in section, having therein a movement from which the dial has been removed to show the spring control of the stem.

Continuing further with the present invention a watch case 1 of the usual construction is shown, having a pendant 2 thereon, in which is provided an L shaped slot 3, which slot, it will be observed, is formed to produce an offset portion at *a*, the purpose of which will be later made clear.

The construction and function of the usual sleeve employed to alternately set and maintain the stem 4 in relative setting and winding position within the pendant, being well known, it is sufficient to mention that no threading is required to be made in the inner periphery of the pendant 2 to receive the mechanism substituted for this sleeve, which is embodied in the invention, and which mechanism constitutes a small rectangular slide 5, disposed within the neck or pendant 2, so as to move longitudinally therein, and at all times impinge upon the shoulder *b* surrounding the stem 4. Exterior control of this slide 5 is accomplished through a small screw or pin 7, centrally secured to the slide 5, extending through the slot 3 and held from displacement therefrom by a shoulder *c* thereon.

In assembling the mechanism to provide accurate control of the winding and setting mechanism, the stem 4 is inserted into the pendant 2 at the lower end thereof, so as to engage the shoulder *b* thereon with the slide 5, whereupon a crown 8 is screwed upon its threaded end, as shown. Being thus held therein, the watch movement is installed in the usual manner, to engage with the squared end of the stem. When this is done, however, the pin 7 naturally assumes a position within the vertical portion of the L shaped slot 3, after being released from the offset portion *a* thereof. In this latter position, the hands may be set upon the face of the watch.

While manipulation of the slide 5 to control the movement of the stem 4 may be successfully accomplished without the aid of a spring, such an element is afforded in the usual watch construction, and with which the invention may co-operate. This ar-

- arrangement is illustrated in Figure 9 which includes a movement 7^a in the case 1 with the dial removed, and an assembly of co-acting levers 8^a and 9^a controlled by a set spring 10.
- 5 It is obvious in this figure that the action of the spring 10 against the lever 8^a is to constantly urge the stem 4 upwardly, and manual pressure against the crown 8 forces the stem back to normal winding position,
- 10 in which position the stem is maintained by a spring sleeve, in cases where this element is employed. However, the present invention proposes to hold the stem in winding position by manipulation of the pin 7, into
- 15 the horizontal or lateral portion of the slot 3.

When it is required to wind the movement, the screw 7 is pressed into position in the lateral portion of the slot 3, and into the offset 20 *a*. This action depresses the stem 4 to its lowest and winding position, and it is restrained from accidental release by the position of the screw 7 in the offset *a*, as provided and heretofore described. To effect 25 setting position, the screw 7 is released from the offset *a* whereupon the said screw assumes its position in the vertical portion of the slot 3, as in Figure 4 and when this is done the stem 4 is released by the slides 5, permitting the stem to automatically move 30 to setting position.

An equivalent structure is also illustrated, which may be employed in preference to the structure described in the foregoing. This 35 structure consists of a small tube 9, shown in Figures 3, 5 and 7. This tube is arranged within the inner periphery of the pendant 2, and through it, the stem 4 is inserted, whereby to permit the shoulder *b* thereon to engage the lower end of said tube, to thus be affected by the actuation of said tube. The screw 7 is threaded into the tube intermediate its ends and is likewise arranged to actuate within the slot 3, whereby to permit 40 of longitudinal movement of the tube within the pendant.

Thus, it is obvious how the present invention aims to overcome the common disadvantage accruing from springing, breaking or otherwise impairing the sleeve used in the 50 winding and setting equipment of the usual watch case structure, and which is usually of very fragile construction, and in addition to this very prominent feature, the invention further dispenses with certain other elements 55 required in the operativeness of the present equipment, to reduce substantially the obvious expense incident thereto, and, to provide a simple assembly arranged for ready repair and convenient access in cases of possible breakage.

It should be herein understood however, that it is not desired that the invention be limited to the specific disclosure herein set forth, and that such minor changes and 60 modifications may be resorted to as fall within the meaning and scope of what is herein claimed.

I claim:

1. A stem controlling mechanism for 70 watches, including in combination with a slotted pendant, and stem, a member arranged to impinge upon said stem within the pendant, means slidable within said slot to move said member longitudinally of said 75 pendant to permit movement of said stem into and out of engagement with the watch mechanism, and means to manually lock said controlling means to hold said stem in winding position within the pendant.

2. In a stem controlling mechanism for 80 watches, in combination with a pendant and stem, means associated with the pendant to engage the stem, means to effect movement of said first means from the exterior of the 85 periphery of the pendant into and out of engagement with the watch mechanism, and means to latch the second means to hold the stem in winding position.

In testimony whereof I affix my signature.

JOHN G. BERGER.
